CLAIM

The ornamental design for a combined tumbler and ice holder, as shown and described.

DESCRIPTION

FIG. 1 is a front elevational view of the combined tumbler and ice holder showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a cross-sectional view thereof.

The characteristic feature of the design resides in the repeating mountain pattern as best shown in FIGS. 1-4 and 6.

FIG. 1

FIG. 2

FIG. 3

FIG. 4

FIG. 5

FIG. 6

FIG. 7
